UNITED STATES PATENT OFFICE.

SAMUEL PETERSON, OF IRON RIVER, MICHIGAN.

CURTAIN AND SHADE HOLDER.

1,227,194.

Specification of Letters Patent.

Patented May 22, 1917.

Application filed August 11, 1915. Serial No. 44,966.

To all whom it may concern:

Be it known that I, SAMUEL PETERSON, a citizen of the United States, residing at Iron River, in the county of Iron and State 5 of Michigan, have invented certain new and useful Improvements in Curtain and Shade Holders, of which the following is a specification.

The invention relates to a combined curtain rod and shade holder, and more particularly to the class of quickly detachable and adjustable curtain rod and shade holders.

The primary object of the invention is 15 the provision of a device of this character, wherein the use of screws or nails for the fastening of the same to a window frame are dispensed with, as the said device can be conveniently and quickly attached in 20 proper position upon the window frame, to support a curtain rod or shade roller.

Another object of the invention is the provision of a device of this character, wherein it may be mounted on various sizes 25 of window frames, for supporting a curtain rod or rods and a shade roller.

A further object of the invention is the provision of a device of this character, wherein the same may be readily and easily 30 attached to or removed from the window frame with despatch, without in the least marring or damaging the latter.

A still further object of the invention is the provision of a device of this character, 35 which is extremely simple in construction, thoroughly reliable and efficient in operation, strong, durable and inexpensive in manufacture.

With these and other objects in view the 40 invention consists in the features of construction, combination and arrangement of parts as will be hereinafter more fully described, illustrated in the accompanying drawings and pointed out in the claim 45 hereunto appended.

In the accompanying drawings:

Figure 1 is a horizontal transverse sectional view through a portion of the device.

Fig. 2 is a perspective view of one of the 50 clamps for the mounting of the device on the window frame.

Fig. 3 is a fragmentary plan view of a slight modification of the invention.

Similar reference characters indicate cor- 55 responding parts throughout the several views in the drawings.

Referring to the drawings in detail, A designates a portion of a window frame, which is of the ordinary well known construction, having mounted thereon the combined curtain rod and shade holder herein-after fully described.

The combined curtain rod and shade holder comprises a pair of window frame clamping members, each including an elongated base plate or section 10, and an adjustable slide section 11, both being formed at their outer ends with right angular jaw terminals 12, provided with inwardly bent spurs or teeth 13, which are adapted to bite 70 into the wood work of the window frame A, at the sides thereof, so that the jaw terminals 12, will firmly grip the same for the fastening of the clamping members thereon. The base plate or section 10, is preferably cut away longitudinally thereof for a portion of its length and at the center of the same to assure lightness thereto, while cut into the side edges of the slot at spaced intervals are outwardly bent guide tongues 14, 80 for receiving the slide section 11, to guide the same in its adjustment.

Formed on the base plate or section 10, are outwardly extending spaced ears 15, and likewise formed on the inner end of the 85 slide section 11, is an outwardly extending ear 16, and swiveled in the said ears 15, is an adjusting screw 17, which is threaded in the ear 16, so that the slide section 11, can be readily moved for attaching or detaching of the clamping member.

On the inner jaw terminal 12, upon each base plate or section 10, is formed a shade bracket extension or bearing 18, which is of the ordinary well known construction, so 95 that both extensions or bearings coöperate for supporting a shade roller, within the window frame, as shown.

Formed on and rising from the upper edge of each base plate or section 10, is a vertical arm 19, having therein near its free end diagonally disposed spaced substantially V-shaped slots or openings 20, while cut from the said arm and working in the latter are resilient lips 21, for detachably locking 100 in the said slots or openings the peripherally grooved ends 22, of substantially U-shaped curtain rods 23, to fasten the same on the clamping members.

In Fig. 3, of the drawings, there is shown 110 a slight modification of clamping member, which is designed especially for double win-

2
dow frames, and comprises the base plate or section 24, and the slide section 25, having the jaw terminals 26, formed with shade bracket extensions or bearings 27, on both of the latter.

From the foregoing it is thought that the construction and manner of use of the invention will be clearly understood, and therefore a more extended explanation has 10 been omitted.

What is claimed is:

In a curtain and shade holder, a base plate having spaced lugs extending from its face to provide a guideway, having ears

extending outwardly at the opposite ends 15 of said guideway, and provided with a rearwardly extending clamping jaw having an extension to support a shade roller, a slide plate mounted in said guideway having one end bent into a clamping jaw and the other 20 end bent laterally to provide an ear formed with a threaded opening therein, and a screw rod swiveled in the ears of said base plate and engaging the threaded opening of the ear of the slide plate.

25
In testimony whereof I affix my signature.

SAMUEL PETERSON.
